UNITED STATES PATENT OFFICE

WILHELM WEMHÖNER, OF BERLIN-NIEDERSCHONWEIDE, GERMANY

CARBURETOR

Application filed September 23, 1930, Serial No. 483,822, and in Great Britain August 11, 1930.

This invention relates to a carburetor with variable air passage cross-section, and it consists substantially in that the cross-section of the narrowed portion is changed by the depression formed in the induction pipe behind same. This depression is automatically regulated according to the invention in such a manner, that it automatically increases as the running speed decreases and decreases 10 as the running speed increases.

In the case of slower running speed therefore the depression is automatically increased in order to utilize the lower boiling point of the fuel caused by the vacuum, as also to 15 homogeneously mix the fuel and air through the good eddy formation caused by the high flowing speed of the gas in the variable narrowed portion, and to surely prevent the knocking of the engine by throttling also 20 with increased compression, in spite of the use of pure benzine.

In the case of faster running speed however the cylinders receive the full charge through the reduction of the depression, so 25 that the thermic degree of efficiency is considerably increased.

In order to automatically regulate the under-pressure in the induction pipe of the engine, a movable piston is preferably used in 30 the form of construction illustrated by way of example, the upper face of which piston is however loaded by the outer atmosphere so that the piston at changing speed is moved in opposition to the direction of the induction. An atomizing element, for example a 35 plate atomizer, is connected with the piston, which at the same time forms the shutting-off element of the induction pipe leading to the engine. This shutting off position is ensured 40 by a spring bearing on the piston and arranged on levers in such a manner, that, on the moving of the piston and opening of the induction pipe, the loading of the spring is 45 more or less removed. Thus, a loading which is inverse to the running speed of the engine is obtained, and consequently the inverse ratio of the depression in the induction to the running speed of the engine is established. 50 An embodiment of the invention is illus-

trated by way of example in the accompanying drawing in which

Fig. 1 is a vertical section through the carburetor.

Fig. 2 is one side view of the carburetor 55 and

Fig. 3 is another side view of the same.

A piston *a* is arranged to move up and down on a column *c* fixed in the carburetor *b*. The piston *a* is extended upwardly like 60 a piston rod and carries on this extension the atomizer device, for example a plate atomizer, consisting of plates *d*₁ and *d*₂. The bore in the column *c* leads to the space situated under the piston, whereas the cover side of 65 the piston communicates with the atmosphere through an aperture *e*. The packing of the piston is effected by a leather diaphragm *f*, which is tied on or otherwise fixed to the carburetor casing at one edge and to 70 the piston at the other edge. The piston is acted upon by a spring *g* shown in Fig. 3, which is adjustably fastened at one end to an elbow lever *h*₁, *h*₂ and at the other end to an elbow lever *i*₁, *i*₂. The elbow lever *h*₁, *h*₂ is 75 pivoted at *h'* on the carburetor casing, and the elbow lever *i*₁, *i*₂ is oscillatably mounted on a shaft *k* journaled in the carburetor casing, on which shaft one or several levers *l* (Fig. 1) are keyed, which engage under a 80 collar *a*₁ of the piston *a*. In inoperative position the spring *g* loads the piston in such a manner that the plate atomizer *d*₁, *d*₂ shuts off the induction channel *m*, leading to the engine, in which channel an air funnel *n* is 85 arranged for this purpose.

If therefore the engine sucks through the induction channel *m* the funnel *n* and the bore of the column *c*, the atmosphere on the piston presses the piston into the position, shown in 90 Fig. 1, so that, in spite of the tensioning of the spring *g*, this spring is relieved when the piston is in the position shown, as the lever arms *h*₂ and *i*₂, rolling the one on the other and which are moved from the dotted position 95 shown in Fig. 3, into the position shown in full line at the strokes of the piston, the operating lever arms alter in such a manner that the lever arm *h*₂ becomes continually longer, whereas the lever arm *i*₁ becomes continually 100

shorter, until in the extreme position shown in Fig. 3, the lever arm i_1 is equal to zero and the loading of the spring is removed from the piston, as this spring acts perpendicularly on the shaft k . Besides the elbow lever i_1, i_2 and catch levers l for the piston a a fuel control lever 2 is also mounted on the shaft k preferably on the side of the carburetor, opposite to that on which the spring g is arranged. This lever o , which in the example shown is in the form of a segment-like disc, has a top pin o_1 adapted to be adjustably inserted in different bores o_2 and o_3 . This pin bears against an arm p oscillatable around p and which shifts by friction an arm q_1 , actuating the fuel needle. The fuel needle is spring loaded.

If the pin o_1 is in the bore shown in Fig. 2, the needle q opens at the beginning of the stroke, that is at the commencement of the induction, first quickly and then slowly. If however the pin is in the bore o_2 , a substantially uniform stroke speed of the needle is obtained during the piston stroke, whereas in position o_3 the needle opens slowly at the beginning of the stroke and then quickly in comparison to the piston speed. The friction between the arms p_1 and q_1 enables, when adjusting the pin or the needle, an immediate bearing of the arm p_1 against the pin o_1 , so that an idle movement between the levers o and p_1 is prevented.

The above mentioned fuel needle q controls the fuel admission in known manner. The fuel, which enters the carburetor at r , passes through a movable pipe s , after having been controlled by the needle q , into the piston and arrives in an annular channel d_3 , whence it passes through upwardly inclined passages d_4 between the plates d_1 and d_2 . The lower plate is perforated from the outer side by passages d_5 extending substantially perpendicular to the passages d_4 . The passages d_4 and d_5 communicate at their admission point between the plates in such a manner that the outer air forcing its way in through the passages d_5 , atomizes the fuel jet, entering through the passages d_4 .

Below the piston a and separated therefrom by a casing wall, a diaphragm t of resistant material is arranged. The space situated under the diaphragm communicates with the induction chamber through the fuel conduit, whereas, like the above described piston a , the space situated above the diaphragm t communicates with the atmosphere through channels q . A valve cone v is rigidly connected with the diaphragm, which cone is acted upon by a spring v_1 in such a manner that, when the carburetor is in the inoperative position, the valve v is closed. Only when the engine commences to suck and the atmosphere entering at u presses the diaphragm downwards, does the valve v open and uncover the passage for the fuel to the regulating needle.

This valve is provided, in order to compensate for the difference in height between the tank and the carburetor. The valve consequently only opens, when a depression exists under the diaphragm t . The valve v must be so set that variations in the height of the reservoir, or overpressure occurring therein, does not effect the quantity of fuel flowing out on the needle.

Having thus described the construction of the carburetor, the operation thereof will be explained so that it is quite clear.

In principle the carburetor only receives further fuel, when the valve v opens, that is, when a certain depression exists under the diaphragm t . The engine then sucks the fuel through the valve v , the conduit w , the needle valve q , the hose s through the piston bore and the atomizer d_1, d_2 . According to the adjustment of the throttle valve, or according to the suction energy, the atmosphere, acting on the piston a , presses the piston a downwards to a greater or lesser extent against the action of the spring g , so that the space situated under the piston a , and therefore the depression existing therein, is reduced until in the position shown in Fig. 1, that is at full speed and with the maximum cross section of the funnel n , the additional loading of the lever h_1, h_2 of the spring g is cut out in the manner described. Consequently the piston a is relieved of this additional loading. Thus the loading inversely to the running speed of the speed of the engine is obtained. The spring g may be suspended on the arms h_1 and i_2 at different distances from the pivot points, in order thereby to regulate any desired depression ratio in the induction line.

The carburetor casing preferably consists of two main parts z_1, z_2 , connected by a clamp screw y (Fig. 3). This dividing of the casing is advantageous in that the upper part z with the throttle valve can be adapted to the type of car, so that only by changing the atomizer plates one and the same main part of the carburetor can be used for all sizes of cars.

I claim:

1. A carburetor with changeable air cross section for internal combustion engines, comprising in combination with the induction conduit, a carburetor casing; a column rigidly mounted in said casing, a piston on said column movable in opposite directions to the direction of induction said piston communicating on the bottom side with the suction chamber and on the upper side with the atmosphere, a spring adapted to additionally load said piston in such a manner that the additional load thereby also the depression in the induction pipe decreases at increasing engine speed and inversely, and a toggle lever to an arm of which said spring is attached so that the lever arm of said spring

decreases when said piston is ascending until at maximum stroke the additional spring loading on the piston is neutralized by said lever arm.

- 5 2. A carburetor with changeable air cross section for internal combustion engines, comprising in combination with the induction conduit, a funnel in said induction pipe, a carburetor casing, a column rigidly mounted
10 in said casing, a piston on said column movable in opposite direction to the direction of induction, said piston communicating on the bottom side with the suction chamber and on the upper side with the atmosphere, a
15 spring adapted to additionally load said piston in such a manner that the additional load thereby also the depression in the induction pipe decreases at increasing engine speed and inversely, a leather cup packing
20 said piston, two atomizer plates on the top end of said piston forming at the same time the closing element for said funnel, and a flexible hose adapted to supply fuel to said movable piston.
25 3. A carburetor with changeable air cross section for internal combustion engines, comprising in combination with the induction conduit, a funnel in said induction pipe, a fuel control needle, a carburetor casing, a column
30 rigidly mounted in said casing, a piston on said column movable in opposite direction to the direction of induction, said piston communicating on the bottom side with the suction chamber and on the upper side with the atmosphere, a spring adapted to additionally load said piston in such a manner that the additional load thereby also the depression in the induction pipe decreases at increasing engine speed and inversely, a leather cup pack-
35 ing said piston, two atomizer plates on the top end of said piston forming at the same time the closing elements for said funnel, a flexible hose adapted to supply fuel to said movable piston, a lever oscillating with said piston, a
40 shaft at the side of said piston, a lever arm downwardly extending from said shaft adapted to be actuated by said piston lever, and a laterally directed lever arm on said shaft adapted to be actuated by friction from
45 said downwardly directed lever arm and to actuate in turn said fuel control needle so that said needle is raised and lowered practically uniformly relative to the piston movement in the beginning quickly and then more slowly, and inversely.
50 4. A carburetor with changeable air cross section for internal combustion engines, comprising in combination with the induction conduit, a funnel in said induction pipe, a carburetor casing, a column rigidly mounted
55 in said casing, a piston on said column movable in opposite direction to the direction of induction said piston communicating on the bottom side with the suction chamber and on the upper side with the atmosphere, a spring
